UNITED STATES PATENT OFFICE.

GEORG HAYN, OF ESSEN-ON-THE-RUHR, AND NORBERT KOCH, OF ESSEN-RELLINGHAUSEN, GERMANY, ASSIGNEES TO FRIED. KRUPP AKTIENGESELLSCHAFT, OF ESSEN-ON-THE-RUHR, GERMANY.

AUTOMOBILE WITH A PIVOT-GUN.

1,079,856.

Specification of Letters Patent. Patented Nov. 25, 1913.

Application filed October 19, 1911. Serial No. 655,601.

To all whom it may concern:

Be it known that we, GEORG HAYN, residing at Essen-on-the-Ruhr, Germany, and NORBERT KOCH, residing at Essen-Rellinghausen, Germany, both subjects of the Emperor of Germany, have invented a certain new and useful Improvement in Automobiles with Pivot-Guns, of which the following is a specification.

10 This invention relates to automobiles with pivot guns and consists primarily in a special arrangement of the platform for the gun.

In the drawing, Figure 1 is a side elevation, partly in section, of one embodiment of 15 the subject matter of the invention; Fig. 2 is a corresponding plan view; and Fig. 3 is a detail.

The pivot support A (Fig. 1) of the gun, 20 is rigidly connected with the frame B of the automobile. In the pivot support, the fork shaped upper carriage D is rotatably mounted through means of a ball bearing a^1 and a vertical pivot d^1 . There is further mounted rotatably upon the frame B, a platform 25 E for the gunner, through the medium of a second ball bearing e^1 concentric to the axis of the gun pivot. The platform carries an armor F, in the rear side of which is provided an opening f^1 , which affords access to

30 the platform E. To facilitate entrance upon the platform, the latter has a recess e^2 (Fig. 2). Upon the upper carriage D is provided an attachment d^2 which serves to receive a coupling bolt d^3 . This bolt engages, with 35 some play, in a recess of the platform E. Upon the platform, at either side of the gun barrel C, ammunition holders G are provided. Two additional ammunition holders H rest upon the automobile frame B.

40 In consequence of the described arrangement of the platform E and its connection with the upper carriage D, the platform will swing together with the gun. Nevertheless, the pivot of the gun barrel is relieved of 45 the weight of the platform, of the serving crew, of the armor, of the ammunition holder G, etc., so that a steady support of the gun is attained.

A securing arrangement is provided for 50 the gun barrel which serves to relieve the aiming mechanism, during the travel of the automobile, by fixing relatively to the latter, the gun system (the gun barrel C, its slide track carrier, etc.) swinging about the axis

of the horizontal trunnion d^4 and the axis 55 of the pivot trunnion d^4 . This securing arrangement consists of a clamp K jointed to a bearing L, mounted on a vertical wall J of the automobile and provided with a recess k^1 shaped to conform to the muzzle end 60 of the gun barrel. Rigidly connected with the clamp K is a lever k^2 , which is jointed to a rod M. The rod M is swingingly mounted through means of an intermediate lever m^1 , upon a bearing m^2 and carries on its end 65 a fork m^3 . This fork is adapted to embrace an eye N, arranged on the platform E and is secured to this eye through the medium of a locking bolt n^1 . The arrangement is so designed that the fork m^3 embraces the eye 70 N when the clamp K stands in engagement with the muzzle end of the gun barrel C (Figs. 1 and 2). The securing clamp K for the gun barrel is thus so combined with a securing arrangement for the platform 75 that when the gun is secured, the platform is simultaneously secured also. When the two securing arrangements are out of operation, they assume the position shown in Fig. 3, in which they will be secured by a means not 80 shown on the drawing, for example, a bolt or an abutment.

We claim:

1. In an automobile having a pivot gun, an automobile frame, a rotary bearing by 85 which the gun is mounted on the frame, and a platform having a rotary bearing on said frame independent of the gun bearing, and securing means comprising a cap and a link, both journaled in the automobile frame, a 90 connecting rod hinged to said cap and said link, an extension member on said rod, a socket on said platform and a key in the socket for engaging said extension member; said cap constructed to fit closely over the 95 gun muzzle, whereby the gun will be held securely in both horizontal and vertical direction, and said platform in horizontal direction when said key engages said extension member.

2. In an automobile having a pivot gun, an automobile frame, a rotary bearing by which the gun is mounted on the frame and a platform rotatable independently of the gun and mounted on said frame, coupling 105 means for connecting the gun and the platform to turn together, and securing means adapted to engage the platform and a part

100

105

of the gun partaking of its elevation and training movement, said securing means being mounted on said frame and connected to the gun and the platform in such a way that when the gun is secured in both horizontal and vertical direction, the platform is simultaneously secured in horizontal direction.

The foregoing specification signed at Bar-
men, Germany, this 28th day of September, 1911.

GEOORG HAYN. [L. S.]
NORBERT KOCH. [L. S.]

In presence of—
ALBERT NUFER,
L. NUFER.
